Primary Examiner — Wendy L Arminio*Assistant Examiner* — Jessica H. Steadman(74) *Attorney, Agent, or Firm* — Greer, Burns & Crain, Ltd(57) **CLAIM**

The ornamental design for a hair clipper as shown and described.

DESCRIPTION

FIG. 1 is a top perspective view of the present hair clipper; FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The subject matter depicted in broken lines depicts portions of the present hair clipper that are not part of the claimed invention.
